UNITED STATES PATENT OFFICE

KARL KARIUS, OF ACHERN-IN-BADEN, GERMANY

METHOD OF ROLLING METALS AND APPARATUS THEREFOR

Application filed December 31, 1925, Serial No. 78,613, and in Germany January 7, 1925.

In rolling section iron with an undercut section member, more particularly in producing channels, the production of an exact channel is difficult, because with the customary method with plain guides a wavy channel results longitudinally of the bar. In consequence of this the channel iron is unusable in cases where an exact fit or tight joint is required.

10 The invention obviates these disadvantages by the provision of special guides which are constructed in such way that before the bar enters or after it leaves the pass, the foot of the bar to be rolled is gradually rolled inward. 15 Further the foot, which has to be turned over, is somewhat thinned down at the folding place so that the fold must occur just at this place.

20 In the drawings the new method is shown by way of example applied to iron frames for glass roofs.

There is shown in Fig. 1 the cross-section of a completed iron frame; in Fig. 2 the cross-section of the iron prior to the formation of 25 the channel; in Fig. 3 a further detail; in Fig. 4 the guide in longitudinal section 4—4 of Fig. 5; in Fig. 5 a cross-section 5—5 of Fig. 4 through the guide; in Fig. 6 the guide in plan. In Fig. 1 *a* is the completed iron frame, in 30 which the glass sheet *b* is held by means of screwed dogs *c* and flat washers *d* between felt or lead strips *e*. It is seen from Fig. 2, that the section up to this point can be easily formed by means of rolling. If according 35 to Fig. 3 the foot is thinned at *f* or alternatively thickened at *g*, the rim *h* will fold at *f*. However this measure alone is not sufficient to produce a satisfactory joint. Only if in the 40 guide 1 Figs. 4 to 6, there is introduced a special guiding fillet, can a joint satisfying all requirements be obtained. The operation of the guide attached like a stripping guide is as follows. The bar previously rolled according to Fig. 3 passes between the rolls *o* and enters the guide in the direction of the arrow, when the twist effects a gradual folding of the rim *h* into the desired position. Then the rim passes gradually behind the projection of the fillet *l* projecting into the guide, which forces the foot of the iron to form with

the greatest possible accuracy a channel satisfying all requirements.

According to the nature of the use to which the channel iron is to be put, it is also possible, for example, if no special accuracy of 55 the channel is required, to use one or the other method alone. Furthermore, the scope of the use is unlimited. For example, it can also be used for the so-called interlocking of grooved and tongued sheet-piling and similar joints. The guide may be passed as well by the channel iron after it has left the rolls. 60

Having now fully described my invention, what I claim and desire to secure by Letters Patent is:—

1. A method of rolling iron sections, consisting in rolling the section to approximate structural form to provide a body and a thinned portion and a thicker rim portion, drawing the section through a guide provided 70 with a twist before the section passes through the finishing rolls to bend the rim only to overlie the thinned portion.

2. A method of rolling iron sections, consisting in rolling the section to approximate 75 structural form to provide a body and a thinned portion and a thicker rim portion, drawing the section through a guide provided with a twist before the section passes through the finishing rolls to bend the rim only to 80 overlie the thinned portion independently of the rolls.

3. A method of rolling iron sections, consisting in rolling the section to approximate structural form to provide a body and a 85 thinned portion and a thicker rim portion, drawing the section through a guide provided with a fillet before the section passes through the finishing rolls, said fillet being provided with a projection into the guide to bend the 90 rim only to overlie the thinned portion.

4. Apparatus for rolling iron sections with undercut section members, including a set of rolls, a guide in advance of the rolls provided with a fillet for imparting a twist to the rim portion only of a section passing through the 95 rolls and guide.

5. Apparatus for rolling iron sections with undercut section members, including a set of rolls, a guide in advance of the rolls provided 100

with a fillet having a projection adapted to bend the rim only of a rim of a section, said guide bending the section independently of the rolls.

6. Apparatus for rolling iron sections with undercut section members, including rolls to shape a section to approximate structural form to provide a body and a thinned portion and a thicker rim portion, finishing rolls, and 10 a guide intermediate the first and second mentioned rolls to bend the rim only to overlie the thinned portion of the section.

In testimony whereof I affix my signature.
KARL KARIUS.
